UNITED STATES PATENT OFFICE.

HARRY R. BARTELL, OF ST. LOUIS, MISSOURI, ASSIGNOR TO CAST STEEL TENDER FRAME COMPANY, OF ST. LOUIS, MISSOURI, A CORPORATION OF DELAWARE.

TENDER FRAME.

Application filed April 3, 1923. Serial No. 629,674.

To all whom it may concern:

Be it known that I, HARRY R. BARTELL, a citizen of the United States, residing at St. Louis, Missouri, have invented a certain new and useful Improvement in Tender Frames, of which the following is a full, clear, and exact description, such as will enable others skilled in the art to which it appertains to make and use the same, reference being had 10 to the accompanying drawings, forming part of this application.

My invention relates to railroad rolling stock and consists in an improved underframe especially adapted for locomotive 15 tenders.

The main object of my invention is to produce an economical underframe for tenders of relatively small capacity, such as are used in industrial or short-haul service. I secure 20 this object by providing a tender frame adapted to be mounted upon a single truck and otherwise supported from the locomotive frame and by forming the underframe of a one-piece casting whereby the metal may 25 be distributed most efficiently by providing sectional areas at different points sufficient to take care of the stresses there encountered without the introduction of surplus metal such as is usually found in built-up struc- 30 tures.

In the accompanying drawings which illustrate a selected embodiment of my invention and the modification thereof.

Figure 1 is a top view of one-half of my 35 improved underframe, it being understood that the other half is a duplicate of that shown.

Figure 2 is a longitudinal vertical section through the center of the underframe.

40 Figures 3 and 4 are transverse vertical sections taken on lines 3—3 and 4—4, respectively, of Figure 1.

Figure 5 is similar to Figure 1 but illustrates a modified construction.

45 Figure 6 is a side elevation of the structure shown in Figure 5.

Figures 7 and 8 are transverse vertical sections taken on lines 7—7 and 8—8 of Figure 5.

50 The underframe casting includes longitudinal draft or center sills 1 and 2 and side sills 3. The longitudinal sills 1 at the left-hand end of the frame merge with the end sill 4 and form therewith a drawbar pocket 5 and are provided also with projections 6

for supporting a removable carry iron 7. The longitudinal sills 2 at the righthand end of the car project beyond the end sill 8 to form members 9 of extended area adapted to be secured to the rear of the locomotive 60 frame 10. Members 9 are provided with projections or flanges 11 whereby they are adapted to cooperate with corresponding surfaces on the locomotive frame and to vertically engage the latter. 65

Intermediate the end sills is a single transverse member 12 which forms a body bolster adapted by means of its removable center plate 13 to rest upon the center plate of a truck bolster. The longitudinal 70 sills 1 and 2 of the frame increase in depth from bolster 12 to the end of the frame and have their maximum depth at the ends.

By means of this construction the tender frame may be mounted upon a single truck 75 located near its longitudinal center and any further necessary support of the truck frame is provided by its connection to the locomotive frame. The increases in depth of the main longitudinal sills of the frame from 80 the bolster toward the ends take care of the loads near the ends of the frame, and the frame as a whole, in combination with a locomotive frame, may be likened to a cantilever construction. 85

The underframe described is economically produced, eliminates one truck from the usual construction, and when combined with the other units of the locomotive and tender 90 assembly materially reduces the tender wheel base and the overall lengths of the tender and locomotive.

The same advantages are retained in the modified construction illustrated in Figures 5, 6, 7 and 8 in which the center plate is 95 not mounted upon a bolster proper but upon a member 14 extending between the center or draft sills 15 and 16 only and formed integrally therewith. This arrangement enables the transverse members 17 and 18 to be located wherever desired and independently of the center of the tender truck. 100

In Figure 5, for example, the two cross beams are provided intermediate the frame ends 19 and 20 without moving the truck 105 supported member from its preferred location and without the provision of a third unnecessary cross member.

In this embodiment of my invention the longitudinal sills 15 and 16 diverge at their 110

forward portions instead of being offset as are the corresponding sills of the preferred form but in both forms the truck supported member is positioned at the inner 5 portions of these draft sills.

In Figures 5 to 8 I indicate equalizer fulcrums 21 and spring shackle brackets 22. Similar elements may be provided on the frame shown in Figure 1 and other additional element attaching means may be provided on either frame. 10

Various other modifications in the proportions and dispositions of the parts shown may be made without departing from the 15 spirit of my invention as expressed in the accompanying claims.

I claim:

1. In a tender one-piece cast underframe, a truck supported bolster positioned intermediate the ends of the underframe, body carrying center, side and end sills and a member projecting at one end of the underframe and adapted to be supportedly attached to a locomotive frame below the plane 20 of said sills.

2. In a tender one-piece cast underframe, a single bolster positioned intermediate the ends of the underframe, and a sill member projecting at one end of the underframe 25 and provided with horizontal surfaces for vertical engagement with cooperating surfaces on a locomotive frame.

3. A tender underframe casting including integrally formed longitudinal sills, end

sills, a single intermediate cross member 35 forming a bolster, a drawbar pocket with carry iron supports at one end of the longitudinal sills and below the plane of said bolster, and an extension at the other end of the longitudinal sills below said plane 40 for attachment to a locomotive frame.

4. A tender underframe comprising a one-piece casting having a transverse member intermediate its ends forming a body bolster, sills merging with said member and extending therefrom downwardly and longitudinally of the underframe to points of maximum depth adjacent to the ends of the underframe. 45

5. In a tender underframe comprising a one-piece casting, longitudinal center sills terminating at one end in a portion adapted to be rigidly secured to a locomotive frame, and a single truck supported member intermediate said sills and spaced from said portion. 50

6. In a tender underframe, a single body bolster intermediate the ends of the underframe adapted to be mounted upon a truck bolster, and longitudinal members extending outwardly and downwardly from each side of said body bolster to points of maximum depth adjacent to the ends of the underframe. 60

In testimony whereof I hereunto affix my 65 signature this 13th day of March, 1923.

H. R. BARTELL.
